UNITED STATES PATENT OFFICE.

DAVID J. MONOSMITH, OF SPENCER, OHIO.

INCANDESCING ELEMENT.

1,030,787.

Specification of Letters Patent. Patented June 25, 1912.

Application filed September 29, 1911. Serial No. 651,948.

To all whom it may concern:

Be it known that I, DAVID J. MONOSMITH, a citizen of the United States, and a resident of Spencer, in the county of Medina and State of Ohio, have invented a new and Improved Incandescing Element, of which the following is a full, clear, and exact description.

My invention relates to incandescing elements admitting of general use, and more particularly to the form of incandescing element especially suitable for use in connection with burners of the so-called "calcium light" type.

More particularly stated, I produce an incandescing element made up of laminae or plates, each plate being weakened by aid of score lines so as to cause the plate to break along said lines in case it breaks at all, thereby preventing fracture of the incandescing element along any line or plane except one parallel with said score lines or with the plates.

My invention further comprehends an incandescing element made up of plates and in which the element after being subjected to heat for the purpose of burning out all combustible matter and driving off all volatile gases or vapors is shrunken by the application of intense heat.

My invention further comprehends various improvements in incandescing elements, the purposes of which are to increase the general efficiency and durability of the latter.

Reference is to be had to the accompanying drawing forming a part of this specification in which like characters of reference indicate corresponding parts in all the views and in which

Figure 1 is a perspective showing a long ribbon or lamina to be used in the construction of my improved incandescing element; Fig. 2 is a perspective showing separate plates made by sub-dividing the ribbon or lamina, and also showing the score lines with which the plates thus made are provided in order to weaken them in certain directions; Fig. 3 is a perspective showing a block made up of plates of the type shown in Fig. 2; Fig. 4 is a perspective showing the finished incandescing element; Fig. 5 is a section through the structure shown in Fig. 4; Fig. 6 shows the ribbon or lamina which, in this instance, is being formed into

an incandescing element by rolling; Fig. 7 is a plan view of the completed incandescing element shown in Fig. 6 as partially formed; Fig. 8 is a section on the line 8—8 of Fig. 7; and Fig. 9 is a perspective showing still another way in which a ribbon or lamina may be formed so as to be built up into the incandescing element.

A long ribbon-like member or lamina 10 is made of a longitudinal piece of fabric permeated with a solution containing a suitable compound, the base of which is of one or more of the rare earths, such as thorium, cerium, or zirconium; the oxids of which are known to be effective in incandescents. Any suitable fabric and any appropriate solution of the kind mentioned may be employed, but in practice I prefer to use a fabric of fibrous material which may have the form of cloth or wadding, as desired, and this fabric is preferably permeated with a solution of nitrate of thorium and nitrate of cerium. The solution is dried out after which the lamina or ribbon is cut into smaller plates 11, and the latter are weakened by score lines 12 which are disposed parallel with each other and with the adjacent edges of the plates 11. These score lines may be cuts extending a little distance into the plates 11, or may be perforations extending entirely through said plates. The manner of making the score lines is not of particular importance, the essential idea being that the plates 11 are to be weakened in any desired manner along lines parallel with each other. The purpose of thus weakening the plates 11 is to enable the finished incandescing element to break in a certain direction whenever subjected to such strain either from heat or mechanical stress as is sufficient to break the element.

The plates 11 are disposed in the form of a pile, as indicated in Fig. 3, the edges of the plates being brought substantially parallel with each other, as indicated in said figure, the score lines 12 also all being parallel with each other. The pile of plates 11 is next subjected to pressure and then to the action of a flame or of intense heat. All organic matter is thus burned out and all volatile gases or vapors are driven off, the only thing remaining being the oxids of the rare earths. These oxids constitute practically a porous framework having generally

the form of a solid block, but consisting of plates parallel with each other, which may or may not adhere together, but in this instance are non-adherent, each plate still retaining its score lines, or, in other words, being weakened at intervals along lines extending parallel with each other.

It is not essential that the plates 11 be permeated with the solution before being 10 formed into a block, as obviously the plates can first be formed into the block and then permeated. After the block is formed, as indicated in Fig. 3, and is burned, as above described, the block is hardened and 15 shranken, as far as possible, by the application of intense heat such as is applied by a very hot flame. I find from experience that the quality of the finished article is 20 greatly improved if the hardening and shrinking be quite thorough. After the hardening and shrinking of the block is finished, one face of the block is rounded slightly, as indicated at 13 in Figs. 4 and 5.

In order to use the incandescing element 25 thus described, it is clamped in a holder so that the rotund face 13 is exposed and the flame, or its equivalent, is directed against the rotund face. I find that the rotundity of the face tends to protect the incandescing 30 element against accidental injury and, moreover, that the incandescing surface thus produced has a suitable form for shedding the light. If, for any reason, either a sudden or gradual variation in the relative temper- 35 ature of different parts of the incandescing element, or because of the element being accidentally subjected to mechanical stress, there is a tendency for the element to split, crack or otherwise break, the injury tends 40 to take place always in a certain direction which, according to Figs. 4 and 5, is toward the right and left; that is to say, the crack, if one is produced, will generally be between two adjacent plates 11 or along a score 45 line 12. A fracture is not nearly so objectionable in an incandescing element, and particularly in the one here under consider- 50 ation, if said fracture extends in the general direction indicated, which is substan- 55 tially at right angles to the incandescing surface to which the flame is applied.

In Fig. 6 the ribbon-like member 14 of impregnated fabric is formed into a roll 15, the finished article being shown at 15^a 55 in Figs. 7 and 8. In this case the incandescing element is provided with a rotund face 16 against which the flame is applied and which becomes incandescent in order to shed light.

60 In Fig. 9 the ribbon-like member 17 of impregnated fabric is bent back and forth upon itself so as to form folds 18, the latter thus forming seams 19, the rest of the process being substantially as above described.

65 The completed structure formed in accord-

ance with Fig. 9 is provided with a rotund face substantially as above described with reference to the other figures.

If the structure shown in Figs. 7 and 8, or that indicated in Fig. 9, be subjected to 70 either a molecular or mechanical strain which tends to break it or its constituent parts, the line of fracture tends to be substantially parallel with certain adjacent edges of the material, and the incandescing 75 element is so arranged that the fracture extends as nearly as practicable directly away from the surface to which the flame is applied for the purpose of producing incandescence.

The incandescing element above described avoids quite a number of objections heretofore urged against incandescing elements of the type suitable for calcium gas-light burners. Among the various objections to such 85 incandescing elements are, first, the relatively small incandescent or light-giving powers of most refractory substances; second, the fragility of the oxids of the rare earths used for incandescing, the fragility 90 of such oxids being very great when the oxids are subjected to the action of intense heat or even mechanical jar or stress; and third, the necessity for using pure or nearly pure oxygen in the burner. I have made 95 the discovery that an incandescing element made as above described effectively avoids all of these objections, and may be used for a relatively long time under comparatively severe conditions.

I do not limit myself to the use of any particular material to be employed in my improved incandescing element, except as above stated or as defined in my claims.

Having thus described my invention, what 105 I claim as new and desire to secure by Letters Patent is:—

1. An incandescing element made up of a plurality of separate plate-like members of incandescing material, the said members 110 being disposed in the form of a pile and pressed together.

2. An incandescing element comprising a plurality of plate-like members, each weakened along a predetermined line, said members 115 being disposed parallel with and in contact with each other and arranged in the form of a pile.

3. An incandescing element, consisting of incandescing material arranged in flat layers one on top of the other to form a pile, the said layers being parallel with each other, the edges of said layers at one end of the element being shaped to form a rounded face at said end for exposure to a flame.

4. An incandescing member built up in layers of material arranged in contact with each other in the form of a pile and pressed together, the edges of the layers at one end of the member being arranged for exposure 130

to a flame, the said layers being parallel with each other and extending in a direction approximately at right angles to the end to which the flame is applied.

5. An incandescing element, comprising incandescing material arranged in flat layers, the layers being disposed parallel with and in contact with each other and pressed together, so that under action tending to 10 break the element the breakage will occur between the layers, the element having a face for exposure to a flame and the layers extending in a direction substantially at right angles to the face to which the flame 15 is applied.

6. An incandescing element built up of plate-like members arranged in the form of a block, said members being weakened along

lines parallel with each other, one end of the incandescing element being rounded for 20 exposure to a flame.

7. An incandescing element having a plurality of layers of incandescing material arranged one on top of the other and pressed together to form a pile, one end of the element being arranged for exposure to a flame, the said layers being each weakened at intervals along lines extending parallel with each other.

In testimony whereof I have signed my 30 name to this specification in the presence of two subscribing witnesses.

DAVID J. MÓNOSMITH.
